UNITED STATES PATENT OFFICE.

JOHN B. CURRAN, OF WESTFIELD, MASSACHUSETTS, ASSIGNOR, BY MESNE ASSIGNMENTS, TO THE FULLER BRUSH COMPANY, OF HARTFORD, CONNECTICUT, A CORPORATION OF CONNECTICUT.

COLLAPSIBLE RECEPTACLE.

Application filed January 25, 1924. Serial No. 683,442.

My invention relates more especially to the class of receptacles usually supported in elevated positions for the purpose of obtaining gravity flow of the contents, as 5 water, for various uses, as for bath purposes, and an object of my invention, among others, is to provide a device of this class that is usually constructed of flexible material, as canvas, with means for enabling 10 the valve in the stop-cock, which is secured to the flexible bottom, to be readily manipulated.

One form of device embodying my invention and in the construction and use of which 15 the objects herein set out, as well as others, may be attained, is illustrated in the accompanying drawings, in which—

Figure 1 is a view in side elevation of a collapsible receptacle embodying my invention. 20

Figure 2 is a detail view, scale enlarged, in vertical central section through my improved receptacle.

Figure 3 is a bottom view of the receptacle. 25

In order to provide for a flow of water, as for bath or other purposes, especially in rural districts where supplies of running water in houses are deficient, it has heretofore been proposed to use a receptacle or 30 bucket that may be placed in an elevated position to cause gravity flow of water therefrom, as through a tube that may be secured to a stop-cock in the bottom of the receptacle or bucket. In order to provide for 35 ready storage of such receptacle, it has been constructed of canvas or similar flexible material attached to a frame, usually of metal, provided with means to permit the receptacle to be collapsed. The bottoms of such 40 receptacles have been composed of the same material, as canvas, as that forming the body of the receptacle, and the stop-cocks for controlling flow of water from the receptacle have been secured to such bottoms, but a dis- 45 advantage has been found to exist in such structures from the fact that the stop-cock being supported by the bottom of flexible material is very unstable as a support, and difficulty has, therefore, been encountered in 50 an effort to turn the valve of the stop-cock, and especially when such valve is somewhat tight, as the flexible bottom will not only give in a vertical direction, thereby permitting the stop-cock to move away from the

hand of the operator and thereby lessen the 55 efficiency of the force applied to the thumb piece of the stop-cock, but a turning movement of the stop-cock is also permitted which lessens the force applied to the thumb piece of the valve, and this is especially true when 60 the valve is somewhat tight, as is usually the case in order to prevent leaking.

My invention, illustrated and described herein, is constructed with a view to eliminate the disadvantages hereinabove set out 65 by providing a rigid support for the stop-cock, in the drawings herein the numeral 5 indicating the receptacle, composed of canvas or other flexible material, and having a bottom 6 composed of the same material. 70

A flange 7 extends around the bottom edge of the receptacle and a stiffening ring 8, as of metal, is commonly employed at the bottom, as well as the top, for stiffening the bottom and top edges, such ring usually 75 being located in a pocket or loop in the top and bottom edges of the receptacle. A stop-cock 9, having a thumb piece 10 secured in any ordinary manner to a valve located within the body of the stop-cock is attached to 80 the bottom 6.

In order to provide for the rigid mounting of the stop-cock, I provide a support 11 that preferably comprises a strip of rigid material, as metal, that extends across the 85 bottom of the receptacle from one side to the opposite side thereof, this band being secured in place in any suitable manner, as by means of angularly disposed ends 12, 90 that are secured, as by riveting or otherwise, to the stiffening ring 8. An opening is formed in this support and the end of the stop-cock is projected through this opening and is secured to the support as by 95 means of a nut 13 fitting the screw threaded end of the stop-cock inside the receptacle and tightly clamping the bottom 6 and support 11 between the nut and a shoulder 14 on the stop-cock, as shown in Fig. 2 of the drawings.

This band provides a rigid support for the stop-cock and enables the latter to resist the forces necessary to turn the thumb piece of the valve, and the latter may, therefore, be readily manipulated, and any undue movement of the stop-cock that would tend to obstruct free turning movement of the valve will be prevented.

In accordance with the provisions of the patent statutes I have described the principles of operation of my invention, together with the device which I now consider to represent the best embodiment thereof; but I desire to have it understood that the device shown is only illustrative, and that the invention may be carried out by other means and applied to other uses than those above set out.

I claim—

1. A receptacle having a bottom composed of flexible material, a stop-cock secured to said bottom for the outflow of liquid from the receptacle, and a support of rigid material secured at its ends to opposite sides of the receptacle and rigidly secured to the stop-cock for support thereof.

2. A receptacle having a bottom composed

of flexible material, with a flange surrounding said bottom, a stiffening ring comprised in said flange, a support extending across the bottom and secured at its opposite ends to said ring, and a stop-cock secured to said bottom and to said support.

3. A receptacle having a bottom composed of flexible material and including a flange extending around the bottom, a stiffening ring of rigid material secured to said flange, a support extending across the bottom and having angularly formed ends secured to said flange on opposite sides of the bottom, and a stop-cock secured to said bottom for outflow of liquid from the receptacle, said stop-cock being rigidly secured to said support.

JOHN B. CURRAN.
